ENGINE STARTER

Filed April 26, 1926

Fig. 2.

Herman G. Richardson INVENTOR

UNITED STATES PATENT OFFICE

WERNER F. BOTHERMUND, OF KEYPORT, NEW JERSEY

ENGINE STARTER

Application filed April 26, 1926. Serial No. 104,685.

This invention relates to engine starters and more particularly to that type of starter wherein a very high rate of power output is obtained for a short period as from a flywheel energized to high speed over a longer period and from a relatively low powered source.

The present embodiment discloses an improved type of starter transmission especially suitable for the starting of engines having relatively massive flywheels such as those of the Diesel type, and provides a means for the starting of such engines without shock, the engine being smoothly accelerated from rest by a mechanism providing a progressively increasing transmission ratio.

One of the principal objects of the invention is to provide a starter having a variable speed transmission of the friction type that has a progressively increasing ratio.

A further object of the invention is to provide a starter of the class described having a transmission that includes a friction drive of progressively increasing ratio starting from a zero setting in which the rate of progression can be readily varied at will to accommodate engines having either light or heavy flywheels.

A still further object is to provide a starter having a transmission of the type described in which a yielding means is included to prevent an overload being imposed on the mechanism such as might result from a back fire in the engine.

Another object of the invention is to provide a starter having the desirable features herein set forth, in which the use of long interconnecting driving members formed of a multiplicity of parts, have been avoided.

Various other objects and advantages of the invention will be in part obvious from an inspection of the accompanying drawings and a careful consideration of the following particular description and claims of one form of mechanism embodying my invention.

In the drawings:

Figure 1 is a vertical section illustrating a preferred form of the present invention.

Figure 2 is a fragmentary view of an alternative form of drive.

In the present instance 10 designates a starting jaw formed on the end of an engine drive shaft adjacent which there is secured to the engine casing (not shown) by any suitable means, a starter housing 11.

Within the housing 11 there is rotatably mounted a shaft 12 having a clutch 13 which is provided with a plurality of angular or helical faces 14. Mounted on the end of the shaft 12 and adapted for relative rotation thereon is a sleeve member 15 supported in a bearing 16, said sleeve member being provided with angular clutch faces similar to the faces 14 and engaging therewith.

Mounted for free rotation upon the shaft 12 is a flywheel 20 provided with a pinion 21, and meshing with this pinion is a gear 22 adapted to be driven by a hand crank 23 or other driving means such as an electric motor. The flywheel is provided with clutch elements 24 adapted to be engaged by a clutch 25 slidably splined to the shaft, said clutch being operated into or out of engagement by a control rod 26 having a lever arm 27 provided with a pin engaging an annular groove 28 formed on the clutch. An actuating means for the control rod consists of a rod 29 engaging a lever arm 30.

Preferably formed as part of the sleeve 15 is a friction disk 32 provided with a face 33 formed of material suitable to frictionally engage for driving a driven member 34 splined to a shaft 35. This driven member is moved axially along the shaft 35 against the pressure of the springs 36, 36 by a device 37 adapted to automatically advance the driven member from an initial zero setting towards the periphery of the friction disk thus gradually accelerating the rotation of the driven member from low to high speed.

The device 37 consists of a partly threaded shaft 38 fixed against rotation in the housing 11, and adapted to be withdrawn therefrom by the removal of a plug 39 screwthreaded in the housing. Several of these shafts each provided with screw-threads of a pitch different from the other may be supplied with each starter to effect either slow or rapid advancement of the driven member 34 along the face of the friction disk, for the purpose of 400

accommodating engines having either light or heavy flywheels, it being obvious that an engine provided with a relatively massive flywheel would require a low rate of acceleration so as to gradually overcome the inertia of the flywheel when started from rest.

Upon the shaft 38 there is mounted a gear 40 having a hub 41, said gear meshing with a relatively small gear 42 formed on the hub 10 of the driven member 34, and a connecting link 43 retains the meshed relation of said gears in their travel either up or down on their respective shafts. In the hub 41 there are pivotally mounted a plurality of segmental members 44 each adapted to engage the threaded portion of the shaft when moved thereagainst by the downward motion of a sleeve portion 45 having a conical shaped bore, and a pair of weighted members 46 also pivotally mounted are adapted, due to 20 centrifugal force to actuate the sleeve 45 downwardly against the segmental members so that they engage the threads when the starter is operated.

At the end of the shaft 35 there is secured 25 a bevel gear 52 meshing with a gear 53 mounted in a bearing 54. The gear 53 is bored to provide a passage for an axially shiftable shaft 55 which the gear drives by means of a spline 56. The shaft 55 has a driving clutch 57 adapted to engage the starting jaw 10, and a shifting means 58 moves the clutch into engagement when the actuating means 29 is operated.

It should be understood that the angular faces 14 of the clutch 13 do the driving (direction of rotation indicated by an arrow) and that these faces tend to force the friction disk 32 axially against the driven member 34 thus intensifying the frictional engagement of these members. A rugged 40 spring 60 settable by a screw 61, bears against the end of the shaft 12 and creates pressure thereon so as to urge the clutch 13 constantly 45 towards its companion.

The spring 60 should be of such a character as to carry a normal driving load in the starting of an engine and to yield when such a load is exceeded and thus permit the 50 angular faces 14 to ride up over those of the sleeve 15 and relieve the driving effort of the friction disk 32 upon the driven member 34.

With reference to Fig. 2 there is shown 55 an alternative driving means in which two friction disks 32^a and 32^b engage the driven member 34^a on either side thus creating a greater driving effort. This form of drive may be employed when it is considered that 60 the single disk type of Fig. 1 would be overtaxed.

The operation of the device is as follows:

Assuming that the parts are in their initial position as shown in Fig. 1, the flywheel 20 is operated to high speed by the hand

crank 23. The rod 29 is then pulled outwardly which causes the clutch 25 to engage the flywheel and simultaneously therewith moves the clutch 57 to engage the starting jaw 10. The stored energy of the flywheel now drives the friction disk 32 at high speed, and the driven member 34 being at the zero setting moves at relatively low speed. The rotation of the driven member also sets into motion the advancing device 37 which causes the sleeve 45 to be moved downwardly against the segmental members 44 in a manner so that they engage the threaded portion of the shaft 38 and cause the driven member to advance, thus progressively increasing the rotational speed thereof which accordingly is transmitted to the shaft of the engine.

When the end of the threaded portion of the shaft has been reached there will be no further advance of the driven member and the device will continue to operate at its highest speed until the engine begins to operate. As the engine overruns the starter mechanism, the clutch 57 will be forced out of engagement with the starting jaw 10 and concomitantly therewith, the clutch 25 will demesh from the flywheel 20. This will bring the friction disk and driven member to rest and the springs 36, 38^a will return the driven member to the zero position.

It will be readily understood that in case of a back fire in the engine the torque imposed upon the mechanism will be in a reversed direction. This reversed torque will not be transmitted to the flywheel, as the angular or helical faces formed on the sleeve 15 will ride over the angular faces 14 of the clutch 13 and permit relative motion between the engaging parts, it being understood that the angular faces of the clutch and sleeve 105 do the driving and not the flat portions thereof. It is obvious that serious damage would otherwise result to the mechanism by a reversed torque against the kinetic energy of the rapidly rotating flywheel.

It is obvious that the shaft 12 may be directly or indirectly driven by any suitable power means such as an electric motor instead of employing the kinetic energy of a flywheel as shown in the drawing, and the substitution of such a driving means for the flywheel is considered to be within the scope of the invention.

It is also obvious that the friction transmission herein disclosed may be advantageously employed with any form of driving mechanism where a progressively increasing speed ratio is desirable at a uniform rate of progression, and accordingly it should be understood that that portion of the invention is not intended to be confined exclusively for use in conjunction with a starter as shown.

Variations may be resorted to within the scope of the invention and portions of the improvements may be used without the other.

ers, whilst not departing from the spirit of the invention.

Having thus described my invention, I claim:

5 1. In a starter, the combination of a flywheel, a means to operate the flywheel to high speed, a friction drive connectible to said flywheel and adapted to transmit a progressively increasing torque to a means to be started, and means by which the rate of progression may be varied at will.

10 2. In an engine starter, the combination of, a flywheel operable to high speed, a driving member connectible to the flywheel, a driven member, the driven member normally disposed at a low speed setting on the driving member, means to gradually advance the driven member during rotation from the low speed setting to a high speed position, means 15 adapted to vary the rate of advance, a power transmission connectible to the engine, and means to return the driven member to its original position when the engine has started.

20 3. In a starter, the combination of a flywheel, a means to operate the flywheel to high speed, a transmission including a frictional driving member and a frictional driven member, a means to connect the driving member with the flywheel for rotation therewith, a 25 spring, a normally engaged clutch in the transmission adapted to permit relative motion of its engaging parts when the power of the spring is exceeded, a means adapted to advance the driven member from an initial 30 low speed position on the driving member to a high speed position while being rotated, means adapted to vary the rate of advance, and a means to connect the transmission to an engine for starting.

35 4. A driving mechanism comprising in combination, a power shaft, a driving member connectible to said shaft, a driven member drivably connectible to a means to be driven, a friction drive between said members giving a speed ratio therebetween uniformly increasing from an initial zero setting, means adapted to change the rate at which said speed ratio is increased, and means 40 for connecting said members respectively to said shaft and to said means to be driven.

45 5. In a driving mechanism the combination with a power means, of a first drive shaft connectible to the power means, a second drive shaft connectible to a means to be driven, a friction drive between said shafts providing a speed ratio therebetween starting from an initial zero setting and adapted to uniformly accelerate the speed of the driven shaft at a predetermined rate of progression, means adapted to change the rate of progression, and means for connecting the said shafts respectively to the power means and the means to be driven.

50 6. A friction transmission comprising driving and driven members in frictional driving

contact and relatively movable so as to provide a uniformly progressive increase in the driving ratio, and means adapted to vary the rate of progression at will.

7. In a friction transmission having an initial low speed setting, the combination of driving and driven members in rolling driving contact, means adapted to provide a constantly progressive increase in the driving ratio of said members at a predetermined rate from zero to maximum, and means adapted to vary the rate of progression.

75 8. A friction transmission comprising members in rolling driving contact and relatively movable so as to provide a uniformly progressive increase in the driving ratio, torque responsive means adapted to intensify the driving contact when the load increases, and means adapted to vary the rate of progression at will.

80 9. A friction transmission comprising members in rolling driving contact and relatively movable to uniformly and progressively increase the driving ratio from zero to maximum, torque responsive means adapted 85 to enforce said contact and to effect said movement, and means adapted to vary the rate of increase.

85 10. In a friction transmission, a driving member, a driven member frictionally engaged therewith and normally disposed at a low speed position adjacent the axis of the driving member, an interchangeable means having a predetermined lead, a means normally out of engagement with the last said means and responsive to rotation so as to cause an engagement therewith and to effect an advance of the driven member from its initial position towards a high speed position.

90 11. A friction transmission comprising in combination a driving and a driven member in frictional driving contact, means adapted to provide a constant progression of the driven member relative to the driving member 95 from an inherent zero starting position in a manner as to attain a gradual acceleration of the driven member to high speed.

100 12. A friction transmission comprising in combination a driving and a driven member 105 in frictional driving contact, a means adapted to actuate the driven member to a zero starting position, and further means adapted to provide a constant progression of the driven member relative to the driving member from 110 the starting position in a manner as to attain a gradual acceleration of the driven member to high speed.

125 13. In a starter, the combination of a flywheel, a means to operate the flywheel to high speed, a friction transmission connectible to said flywheel and to a means to be started; said transmission comprising a driving and a driven member in frictional driving contact, a means adapted to actuate the driven 130

member to an initial zero starting position, and a further means adapted to provide a constant progression of the driven member relative to the driving member from said starting position in a manner as to attain a gradual acceleration of the driven member to high speed.

Signed at Keyport, in the county of Monmouth and State of New Jersey this 24th
10 day of April, A. D. 1926.

WERNER F. ROTHERMUND.
